UNITED STATES PATENT OFFICE.

ROBERT M. MITCHELL, OF CHICAGO, ILLINOIS, ASSIGNOR TO INTERNATIONAL HARVESTER COMPANY, A CORPORATION OF NEW JERSEY.

CORN SHELLER.

Application filed March 3, 1919. Serial No. 280,432.

To all whom it may concern:

Be it known that I, ROBERT M. MITCHELL, a citizen of the United States, residing at Chicago, in the county of Cook and State of Illinois, have invented certain new and useful Improvements in Corn Shellers, of which the following is a full, clear, and exact specification.

This invention relates to cornshellers and 10 more particularly to shellers of the cylinder type.

The object of the invention is to provide a construction which will have a maximum capacity for the size of the cooperating elements, and a construction in which the shelling elements are capable of a fine adjustment with respect to each other, whereby a thorough and efficient shelling of the corn is obtained, and also to provide a structure by 20 means of which the shelled corn is thoroughly separated from the cobs and chaff or other foreign matter.

One embodiment of the invention has been illustrated in the accompanying drawings, 25 and in these drawings,—

Figure 1 is a vertical longitudinal sectional view of the entire machine showing the various parts and their relative locations with respect to each other;

Fig. 2 is a longitudinal sectional view of the shelling cage and shelling cylinder and the supporting brackets for the shelling cage;

Fig. 3 is a plan view showing the elements 30 which make up the shelling cylinder as spaced apart from each other, but in position to be assembled;

Fig. 4 shows an end elevation or edge view of a section of one of the shelling rings;

Fig. 5 is a transverse sectional view on an enlarged scale of the shelling mechanism showing means for adjusting the shelling staves which form the shelling cage;

Figs. 6 and 7 illustrate in plan and in 45 transverse section one of the shelling staves;

Figs. 8 and 9 are sectional views on an enlarged scale showing the shelling staves, sectors and cam ring for adjusting the sectors and staves;

Fig. 10 shows an elevation of the cam ring, the shelling mechanism being shown in section;

Fig. 11 is a plan view of the cam ring;

Fig. 12 shows in elevation on an enlarged 55 scale, one of the shelling stave sectors;

Fig. 13 is a view taken at right angles to Fig. 12 and illustrates a portion of a section of a shelling stave sector;

Fig. 14 is a plan view of the lower half of the cam ring showing the connection of the 60 adjusting links thereto;

Fig. 15 is a sectional view illustrating the construction of the other half of the cam ring and taken on line 15—15 of Fig. 11;

Fig. 16 is a sectional view showing the 65 shelling stave sectors, cam ring and shelling cage bracket; and

Fig. 17 is an end elevation of the shelling cage head.

The general construction and locations of 70 the various elements utilized in my improved corn sheller are illustrated in the sectional view in Figure 1, and in this figure are shown the hopper 20, shelling mechanism 21, shelled corn separating mechanism 22, shelled 75 corn delivery mechanism 23, dust and chaff discharging mechanism 24, and cob elevator 25.

The various parts of the mechanism are 80 supported in the present instance on a truck frame carried by wheels 26 and comprising horizontal longitudinal frame members 27, vertical frame members 28, and transverse horizontal frame members 29 which may be of any suitable construction. The corn shell- 85 ing mechanism which in this instance embodies a rotating shelling cylinder surrounded by a stationary adjustable shelling cage, will first be described.

A shaft 30 is journaled in suitable bearings 31 carried by the machine frame, the central portion of the shaft being enlarged as shown at 32 and square in cross section, and the outer portions being reduced. A 90 collar 33 is screw-threaded onto one outer end portion of the shaft and forms a seat for one end of a conical feeding member 34 which is provided with an annular channel 35 in which is seated the collar 33. The feeding member 34 is provided with spiral 95 ribs 35' which assist in feeding the material fed in the hopper 36 rearwardly to the shell- 100 ing mechanism. A cylindrical supporting member 37 is secured to the central portion 32 of the shaft 30 against longitudinal move- 105 ment by any suitable means, such as the set screw 38, and said cylinder is provided on its outer surface with a series of longitudinal ribs 39, these ribs being provided for the purpose of positioning the shelling rings 110

which make up the shelling cylinder, as will be hereinafter more fully described.

The shelling cylinder is provided with a series of shelling rings 40, each of said rings being made up of two semi-circular sections 41, one of these sections being illustrated in Fig. 4. The construction of these rings and the method of assembling the rings on the supporting cylinder should be particularly noted, since these rings are so constructed and assembled that if a break occurs in one of the rings, the inter-engaging portions of the broken parts of that ring with corresponding portions on the adjacent rings, will prevent the broken parts from being separated from the remaining parts, and will therefore prevent injury to the cylinder and the possible wrecking of the machine.

Each of the sections of the shelling rings is provided at each edge with two sets of outwardly projecting arcuate lugs 42 and 43, the lugs 43 being located on one circumference and the lugs 42 being located on another circumference, the circles or circumferences being concentric and having as their center the center of the shelling cylinder. The inner surfaces of the shelling rings are provided with inwardly projecting lugs 44 which are spaced apart to form a notch 45 for the reception of the longitudinal ribs 39 on the supporting cylinder 37.

In assembling the sections of the shelling rings on the supporting cylinder, the breaks between the two sections of adjacent rings are disposed in staggered relation so that the breaks between the sections of one ring will not come opposite the breaks between the sections of the adjacent rings. The sections are also so positioned on the cylinder that the lugs 43 on the sections of one ring will overlap and interlock with the lugs 42 on the sections of the adjacent ring. Figure 3 which shows the shelling rings spaced apart, clearly illustrates the relative positions of these rings as they are ready to be assembled. The rings are all provided with outwardly projecting ribs 46 which engage the ears or cobs and assist in shelling the corn. The shelling ring disposed at the inlet or front end of the shelling cylinder is provided on one edge with the arcuate lugs 42 and 43 and on its opposite edge is provided with a beveled portion 47 which engages a corresponding beveled portion 48 formed on the rear end of the feeding member 34. The rear end of the cylinder is closed by what may be termed a head ring 49 provided on its outer surface with ribs 50 corresponding to the ribs 46 on the shelling rings, and having a beveled channel portion 51 adapted to engage with a beveled projecting portion 52 formed on the end shelling ring. The head ring is also provided with a central aperture through which one reduced end portion of the shaft 30 extends, the head ring being

properly positioned on this shaft by means of a hub 53 having an arcuate engaging portion 54 which engages with a corresponding arcuate portion 55 formed on the head ring, as clearly illustrated in Fig. 2. A locking collar 56 may be placed on the shaft 30 to secure the hub 53 against displacement. By means of this rocking or self-aligning connection between the head ring and the shaft 30, the proper positioning of the head ring and of the shelling cylinder is assured.

Having described in detail the construction of the shelling cylinder, the construction of the shelling cage will next be considered.

The shelling cage is made up, briefly, of four parts, namely, the staves (which form the cage), the stave sectors, the cam rings (which adjust the stave sectors and staves), and the shelling cage brackets. In Fig. 5 I have illustrated the shelling cage brackets 57 which are secured in any suitable manner to the frame members 27. These brackets are bolted to each other by suitable bolts 58, and form together what may be termed the shelling cage heads.

It will be understood without further description that one of these heads is positioned at each end of the shelling cylinder as shown in Fig. 1, and in the following description I will limit myself to a single head, it being understood that the two heads are exactly similar.

Each of the heads is provided with a series of notches 59 circumferentially located, and reinforced by inwardly projecting lugs 60. The purpose of the notches is to prevent the rotation about the shelling cylinder shaft of the shelling stave sectors by the cam rings when these sectors are being adjusted. The cam rings 61 are positioned on the insides of the flanges 62 of the shelling cage brackets, and are angular in outline as shown in Fig. 9. Each of the cam rings is made up of two sections as illustrated in Fig. 11, and each section is provided with a series of eccentric lugs 63 and with bearing surfaces 64 concentric with said lugs. The lugs and bearing surfaces are adapted to engage corresponding portions on the shelling stave sectors 65, said sectors having channel portions 66 to engage the lug 63 on the cam rings and having outer surfaces 67 to engage the bearing surfaces 64 on the cam rings. The shelling stave sectors are also provided with laterally projecting lugs 68 which are adapted to be received in the notches 59 of the shelling cage heads, as illustrated in Figs. 16 and 17. The sectors are each provided with channels 69 which are adapted to receive arcuate lugs 70 formed on the outer ends of the shelling staves 71, whereby as the sectors are moved toward and from the cylinder shaft, the staves will be correspond-

ingly moved. Lugs 72 are also formed on the stave sectors and engage with shoulders 73 formed on the cam rings, thereby limiting the movement of the stave sectors to expand the shelling cage.

In Fig. 5 the shelling cage is shown in expanded position, and in Fig. 10 the dotted line showing illustrates the contracted position of the cage. In connection with the adjustment of the cam ring I have provided means for obtaining an exceedingly fine adjustment, and means whereby the shelling cage may be contracted or expanded in exceedingly small increments. This mechanism is illustrated in detail in Figs. 5, 10 and 14, and comprises a crank 74 journaled in a bracket 75 secured to one of the frame members 27 and having a screw threaded sleeve 76 receiving the threaded end 77 of a link 78. The link 78 is pivotally connected at 79 with a link 80 which is pivoted at its opposite end on a pin 81 carried by the lower section of the cam ring 61. A cotter pin 82 is provided on the outer end of the pin 81 to prevent the accidental removal of the link 80.

The method of operating the adjusting mechanism for the shelling cage will now be briefly described, it being understood that the shelling cage at each end of the cylinder is provided with separate adjusting mechanism whereby the opposite ends of the shelling staves may be adjusted independently.

In adjusting these staves the usual custom is to space the inlet end of the staves at a greater distance from the shelling cylinder than the outlet ends, for the reason that the inlet ends receive the corn cobs in substantially their normal condition, whereas as the cobs pass from one end of the cylinder to the other, they are broken up and the corn is shelled therefrom.

When the operator desires to adjust the shelling staves he rotates the crank 74 thereby through the links 78 and 80 rotating the cam ring in the shelling cage brackets. As the cam ring is rotated, the shelling stave sectors 65 are forced by the cam rings toward or from the center of the cam ring or the shelling cylinder shaft by means of the engagement of the lug 63 and bearing surfaces 64 on the cam ring with the channels 66 and bearing surfaces 67 on the stave sectors. The lugs 68 on the stave sectors engaging with the notches 59 on the shelling cage heads, prevent the rotation of the stave sectors. As the shelling stave sectors are moved toward and from the center of the cam ring or the shelling cylinder shaft, the sectors will carry with them the shelling staves 71, since the lugs 70 carried by the shelling staves are retained in the channels 69 formed in the sectors.

As the corn is being shelled it passes

through the shelling cage and certain of the shelled corn drops through the longitudinal slots 83 formed in the shelling staves 71, and in order to direct this shelled corn downwardly to the separating mechanism, I have provided an inclined chute 84, the upper portion of this chute being closed and, preferably, formed of sheet metal as shown at 85, and the lower portion of the chute being provided with a series of spaced longitudinal members 86 forming a comb. In order to separate the shelled corn which passes out at the outlet end of the shelling cage and also passes downwardly over the chute 84, I have provided a series of sets of rotatably mounted, intermeshing, triangular shaped disks 87, preferably formed of steel. These disks are driven in the direction of the arrow shown at A in Fig. 1, any suitable driving connections being utilized.

I have illustrated diagrammatically and in dotted lines in Fig. 1 a series of gears 88 carried by the shafts on which are supported the sets of disks, and a series of idler gears 89 interposed between the gears 88, in order that all of the sets of disks may be rotated in the same direction. As the shelled corn, chaff and husks or other foreign material, are being fed rearwardly by the rotating disks, the shelled corn passes down between the disks onto an inclined chute 90, or an inclined chute 91, and by means of these members is directed to the shelled corn elevator 23. The cobs which are conducted to the rear of the shelled corn separator, pass downwardly through a chute 92 to a cob elevator 25, the chute 92 being provided at its front end with a series of longitudinally projecting spaced teeth 93 which form a comb and overlap the rearwardly positioned set of disks, thereby preventing any of the cobs from falling downwardly onto the chute 91. In order to assist in removing the husks, chaff, and foreign matter from the shelled corn as it passes over the shelled corn separator, a fan 94 is positioned below the separator and directs a blast upwardly through the rotating disks, thereby blowing the light material such as dust, chaff, husks and other foreign matter, upwardly. A suction fan 95 is positioned above the exit end of the separator and directs the chaff and foreign matter blown upwardly by the fan 94 into a delivery member 96 by means of which it is removed from the machine.

Having described the various elements which constitute my improved corn shelling machine, I will now briefly set forth the complete operation of these elements.

As the corn is fed into the machine through the hopper 20, it is received by the feeding member and is fed to the shelling cylinder by means of which the husks and kernels of corn are removed from the cobs.

A part of the shelled corn passes through the slots in the staves and the remainder of the shelled corn, cobs, husks and other foreign matter, passes out at the outlet end of the shelling cage. The corn passing through the slots in the staves is directed downwardly by the chute 84 to the shelled corn separating mechanism, and the material passing out at the outlet end of the shelling cage drops directly on this separating mechanism. By means of the rotating sets of intermeshing disks the shelled corn is separated from the cobs, husks and foreign matter and passes between these disks onto chutes 90 and 91, by means of which it is directed to the shelled corn elevator mechanism, 23. The chaff, husks, and foreign matter are blown upwardly by the fan 94 and are removed from the machine by the suction fan 95, and the cobs pass down the chute 92 to the cob elevator 25.

Although I have described but one embodiment of my invention, it should be understood that the invention is capable of many modifications. Changes, therefore, in the construction and arrangement of parts may be made which do not depart from the spirit and scope of the invention as expressed in the following claims.

30 I claim:

1. Shelling mechanism for corn shellers comprising in combination, a cylinder, a shelling cage enclosing said cylinder and including a plurality of adjustable staves, stave sectors engaging said staves, and cam mechanism engaging said stave sectors.

2. Shelling mechanism for corn shellers comprising in combination, a cylinder, a shelling cage enclosing said cylinder and including a plurality of adjustable staves, stave sectors engaging said staves, means for adjusting said stave sectors, and means for preventing the rotation of said stave sectors about the center of the shelling cylinder as an axis.

3. Shelling mechanism for corn shellers comprising in combination, a bracket, a cam ring carried by said bracket, stave sectors mounted in said cam ring and having portions engaging said bracket, and shelling stave carried by said stave sectors.

4. Shelling mechanism for corn shellers comprising in combination, a cylinder, a shelling cage enclosing said cylinder and including a plurality of adjustable staves, stave sectors engaging said staves, a shelling cage head, and means carried by said sectors and engaging said head for preventing rotation of said sectors.

5. Shelling mechanism for corn shellers comprising in combination, a cylinder, a shelling cage enclosing said cylinder and including a plurality of adjustable staves, stave sectors engaging said staves, means for

adjusting said stave sectors, a shelling cage 65 head having a series of circumferential notches therein, and lugs carried by said stave sectors and engaging said notches for preventing the rotation of said sectors as said sectors are adjusted.

6. In a corn sheller, a shelling cylinder comprising a supporting member having outwardly projecting ribs, and a plurality of sectional shelling rings mounted on said member and having inwardly extending portions adapted to engage said ribs, each of said ring sections having portions interlocking with corresponding portions on the adjacent sections.

7. In a corn sheller, a shelling cylinder 80 comprising a supporting member and a plurality of sectional shelling rings mounted on said member to rotate therewith, each of said sections having lugs projecting outwardly from its opposite edges, the lugs at 85 one end being disposed in a different circumferential surface from those at the opposite end and longitudinally alined therewith.

8. In a corn sheller, a shelling cylinder comprising a supporting member and a plurality of sectional shelling rings mounted on said member to rotate therewith, each section of said shelling rings being provided on each edge with a plurality of sets 90 of outwardly projecting lugs, certain of said lugs being disposed in different circumferential surfaces from certain others of said lugs.

9. In a corn sheller, a shelling cylinder comprising a supporting member, and a plurality of shelling rings mounted on said member to rotate therewith, each of said rings comprising a plurality of sections and each section having portions interlocking with corresponding portions on adjacent 105 sections, said rings being so mounted on said supporting member that the junction of the two sections of one ring will be disposed in a different longitudinal plane passing through the center of the shelling cylinder 110 from the junction of the sections of the shelling rings adjacent thereto.

10. In a corn sheller, a shelling cylinder comprising a supporting member having outwardly projecting ribs, and interlocking shelling rings having inwardly extending portions adapted to engage said ribs.

11. In a corn sheller, a shaft, a feeding member carried thereby, a shelling cylinder comprising a plurality of shelling rings, the shelling ring adjacent said feeding member having a portion overlapped by the exit end of said member, a head ring disposed at the opposite end of said shelling cylinder, and a self-aligning connection between said head ring and said shaft.

In testimony whereof I affix my signature.
ROBERT M. MITCHELL.
